UNITED STATES PATENT OFFICE.

PHILIP APPLEBY ROBSON, OF LONDON, ENGLAND.

COMBINED ASH-RECEIVER AND PAPER-WEIGHT.

SPECIFICATION forming part of Letters Patent No. 747,227, dated December 15, 1903.

Application filed February 9, 1903. Serial No. 142,503. (No model.)

To all whom it may concern:

Be it known that I, PHILIP APPLEBY ROBSON, a subject of the King of Great Britain, and a resident of Westminster, S. W., London, England, have invented new and useful Improvements in a Combined Ash-Receiver and Paper-Weight, of which the following is a full, clear, and exact description.

The present invention relates to certain novel and useful improvements in ash-receivers, and has particular application to an article of this character which shall serve both as an ash-receiver and as a paper-weight, while at the same time it is so constructed that it may be used as a pipe-cleaner.

In carrying out the present invention I have in contemplation the provision of an article such as above described, which is formed either by one casting or with a steel spike and has extending centrally upward from the ash-receiving well a relatively long tapered spindle or spike, which may be used as a means for cleaning or removing burned particles of tobacco or ashes which cling to the interior wall of the bowl of a pipe.

A further object of the invention is to provide an article which shall have the base or body portion so formed that it shall serve as a paper-weight, such body portion being preferably so ornamented or shaped that a very pleasing effect is attained. The body portion is also of such weight or heaviness that it will be impossible to tip or turn the article over by an ordinary jar, thereby avoiding the scattering of ashes over the table or floor, as often occurs in the use of ash-receivers. The under surface of the body portion may be covered with leather or cloth to prevent scratching tables or other surfaces on which said body portion rests.

It is also my intention to combine an ash-receiver and paper-weight which shall embody the essential and desired features of durability and simplicity.

With the above-recited and other objects of a similar nature in view my invention consists in the peculiar construction, combination, and arrangement of parts, as is herein described in this specification, delineated in the accompanying drawings, and set forth in the appended claims.

Reference is to be had to the accompanying

drawings, forming a part of this specification, in which similar characters of reference indicate corresponding parts in both the figures. 55

Figure 1 is a perspective view of an ash-receiver and a paper-weight embodying my improvement, and Fig. 2 is a central vertical sectional view taken on the line 2-2 of Fig. 1.

In the accompanying drawings, wherein I have shown an embodiment of my invention, A designates the base or main body portion of the device, which is formed of any heavy weighty material—such as cast-iron, lead, or other metal—and in some instances may be formed of glass, china, earthenware, or the like. This base portion is formed with a hollow interior well portion B, and the vertical wall of said body portion, which in the present instance is shown of cylindrical form, 70 preferably converges upward, so that said base portion is frusto-conical in conformation. The upper circumferential edge portion C of the aforesaid base is slightly rounded or tapered, so as to be of less diameter in cross-section than the remaining portion of the wall of the well, thus enabling ashes brushed from a cigar or knocked from the pipe to move down the inclined side into the well. Extending upward from the center of the 80 well portion is a spike or tapered spindle formed, preferably, as shown in Fig. 1—that is, with a round or cylindrical base portion D and a pyramidal extended body portion E, having an acute apex formed by the convergence of its sides. By this construction it will be evident that a pipe-bowl may be readily cleaned upon the spindle or spike, the sharp corners formed by the juncture of the faces of the pyramid following the walls 85 of the pipe closely and removing therefrom the accumulations of ashes or partly-consumed tobacco. If desired, cigar and cigarette holders F may be formed circumferentially of the well.

While I have in the present instance shown and described one particular embodiment of my invention, it is of course to be understood that I do not limit myself to the precise construction of details shown herein, as there may be modifications and variations in some respects without departing from the principle of the invention or sacrificing any of the advantages thereof. For instance, the

central spindle or spike might be of another shape or form from that described, and the body portion or well might be of any approved character. It will be evident that the cigar or cigarette rests F can be formed of any suitable shape or material and may be arranged circumferentially of the rim of the well, as shown in the drawings, or may be attached around the sides thereof without affecting the invention.

Having thus described my invention, I claim as new and desire to secure by Letters Patent—

1. An article of the class described, comprising a main body portion approximately circular in cross-section, the upper circumferential edge of said body portion being inwardly inclined and of reduced diameter in cross-section, and a spindle mounted centrally in the well and extending above the upper edge thereof, said spindle having a rounded base portion, and an approximately

pyramidal extension mounted on said rounded base portion, substantially as set forth.

2. An article of the class described, comprising a body portion having a well formed therein, the upper edge of the vertical wall of the well being inclined inwardly, cigarette rests spaced apart and formed integral with the upper edge of the well, and a spindle extending upward from the center of the bottom of the well, said spindle comprising a rounded base portion and a tapered portion approximately a square pyramid mounted upon the rounded section, substantially as set forth.

In testimony whereof I have signed my name to this specification in the presence of two subscribing witnesses.

PHILIP APPLEBY ROBSON.
